MOBILE STORAGE UNIT

Gordon Smith, Greenwich, Conn., and George H. Kress,
East Orange, N.J., assignors to Business Supplies Cor-
poration of America, New York, N.Y., a corporation
of Massachusetts

Filed Apr. 30, 1968, Ser. No. 11,718

Term of patent 14 years

Int. Cl. D12—02

U.S. Cl. D14—3

FIG. 1

FIG. 2

FIG. 3

FIG. 4

FIG. 1 is a perspective view of a mobile storage unit, showing our new design;

FIG. 2 is a perspective view of one of the modules in the mobile storage unit of FIG. 1;

FIG. 3 is a perspective view of the module of FIG. 2 with one of the storage cells in an open position;

FIG. 4 is a perspective view of the module of FIG. 3 with the three storage cells in an open position.

We claim:

The ornamental design for a mobile storage unit, as shown and described.
